UNITED STATES PATENT OFFICE.

GEORGE LUTZ, OF LANCASTER, OHIO.

IMPROVED WATER-INDICATOR FOR STEAM-BOILERS.

Specification forming part of Letters Patent No. 39,821, dated September 8, 1863.

To all whom it may concern :

Be it known that I, GEORGE LUTZ, of Lancaster, in the county of Fairfield and State of Ohio, have invented a certain new and useful Improvement in Water-Indicators for Steam-Boilers, of which the following is a full, clear, and exact description, reference being had to the accompanying drawings, which make part of this specification, and in which—

Figure 1 represents a view in elevation of a water-indicator embracing my improvement; Fig. 2, a vertical central section through the same, and Fig. 3, a vertical section through the same at the line *x x* of Fig. 1.

In water gages or indicators for steam-boilers as heretofore used much inconvenience and error is experienced, owing to their complex construction.

It is the object of my invention to render the indicator more uniform and certain in its operation by simplifying its construction and reducing the number of its members; and to this end my invention consists in combining with a pinion on the index-shaft a ratchet on a rod or bar, (that is connected to a crank-arm,) and the float attached to a rod, the opposite end of which is fastened to the projecting end of the rock-shaft which carries the crank-arm. An index, *I*, is secured upon a suitable journal carrying a toothed pinion, *o*. One end of this journal rests in the rear plate of the indicator, while the other end of the journal is secured in a plate, *K*, having flanges by which it is fastened with screws to the back plate of the indicator. The index *I* and graduated plate *G* are contained within a close box, having a glass front in the usual manner, and the index vibrates over the numbers on the graduated plate to mark the depth of water in the boiler. This box is connected to the boiler or to the box *Y* within the boiler by a tube or pipe, *B*, having suitable screws at each end, the one to connect with the box containing the index and the other to make a steam-tight joint above and below the boiler-plate at the point of attachment. The plate *K* has one of its flanges placed far enough from the pinion to receive the ratchet end of the rod or bar *S*, and holds the toothed portion of the bar always in gear with the pinion. This ratchet-bar passes down through the connecting-pipe *B*, and is attached at its lower end to the crank-arm *t*, secured on a rock-shaft in

the box *Y*. This box is cast in one piece, with one of its sides open, and with a flange at the top to make a steam-tight joint on the under side of the boiler, being held in place by a nut, *X*, on the connecting-pipe. The open side of the box *Y* is closed with a screw-cap, *y*, having a central depression to receive the inner end of the rock-shaft *A*, the whole box being of a capacity to admit the easy vibration of the crank-arm on the rock-shaft. A collar on the solid side of the box is drilled centrally to receive and support the rock-shaft in a horizontal position. The rock-shaft is pivoted at one end in the central bearing of the screw-cap, and rests in the collar *y'*, through which it passes at the other end, having a flange on it that fits neatly on the inside of the collar to keep it in place, and a suitable stuffing-box on the inside of the collar to make the box steam-tight.

Instead of a stuffing-box I employ a screw-nut, with a spiral spring on the rock-shaft. One end of this spring bears against the inside collar on the shaft, and the opposite end bears against the nut, so as to pack the joint with the least possible friction, and yet keep it always perfectly steam-tight.

From the projecting end of the rock-shaft a bar, *C*, extends longitudinally into the boiler, having a float upon it that rests on the water in the boiler. This float may be adjustable on the bar that carries it, or it may be fastened on one part of the bar permanently.

It is obvious that moving the crank wrist or pin nearer to or farther from the rock-shaft will change the movement of the index, and other modes of varying its movements are of almost obvious suggestion.

The operation of my improvement is extremely simple and direct. As a change of the quantity of water in the boiler occurs, a change instantly takes place in the vertical position of the float. This moves the rock-shaft, which rises or depresses the ratchet which turns the pinion, and thus vibrates the index to the proper number to indicate the quantity of water in the boiler.

I am aware that a float has been used at the end of a rod working in a packed or close joint, and connected by a slotted lever with an index, as in the patent to F. A. Hoyt, dated July 25, 1859, No. 24,874; but this I do not claim.

The mode of packing the crank-shaft and connecting the crank-arm therewith, to operate the index, presents a clear and well-defined improvement, both in the construction and operation of my water-indicator, over and above what is shown in the said patent.

What I claim as my invention, and desire to secure by Letters Patent of the United States, is—

The combination and arrangement of the pinion, ratchet, rock-shaft, and float, substantially as set forth, for the purpose specified.

In testimony whereof I have hereunto subscribed my name.

GEORGE LUTZ.
